CARTON FOR FRAGILE ARTICLES

Ray H. Fitz Gerald, Nashville, Tenn.

Application June 5, 1956, Serial No. 589,517

3 Claims. (Cl. 229—28)

a partially folded state, from which complete erection of the carton is extremely fast and simple.

Referring to Figure 1, the blank, generally designated 10, from which the carton is constructed, is constituted by a single elongated sheet of material, preferably a fibrous board. The blank is scored along a series of parallel lines 12, 14, 16, 18, 20, 22, and 24 to define the following parts in succession: a false bottom or cushion 26, a false or inner rear panel 28, a top 30, a front panel 32, a bottom 34, a rear panel 36, a cover 38, and a frontal locking lip 40. The entire blank may be perforated along a median line 42 so that the carton may be divided into halves when finally constructed, if desired. Cushion 26 is scored along a center line 44 and is provided with a row of triangular slots 46 each having a vertex on line 44 and a side perpendicular to the line as shown. The cushion is slit as indicated at 48 in generally H-shaped configurations. The false rear panel 28 may be provided with a suitable adhesive 50 for a purpose to be described. Top 30 is slit along the solid lines shown, such as lines 52 and is cut out as indicated at 56. In addition the top may be scored along the dotted lines such as 54. The bottom 34 is provided with at least one aperture, such as 58. The frontal lip 40 is formed with a conventional egg carton lock, such as a plurality of tongues 60 separated by a plurality of grooves 62.

The packer may be provided a blank in completely unfolded state, as shown in Figure 1, or in a partially folded state. To place the blank in the latter state, the blank 30 is folded back upon itself to form a first fold at line 20, a second fold at line 16, and a third fold at line 12, as shown in Figure 2A. The false rear panel 28 may then be secured to the rear panel 36 by employing the adhesive 50 or any other suitable means. With the blank folded as just described, the false bottom or cushion 26 will lie sandwiched between the top 30 and the bottom 34 and will extend diagonally from the fold at line 12 toward the fold at line 16. It will be observed that the width of the cushion 26 between these folds is significantly greater than the width of the bottom 34 between lines 18 and 20 and that the height of the rear panel 36 between lines 20 and 22 is significantly greater than the height of the false rear panel 28 between lines 12 and 14.

In the state just described, the blank is still substantially flat, since it has not been bent along any of the other score lines, and accordingly the blank consumes little storage or shipping space. When the carton is to be erected for filling, the cover is bent back along line 22. Then the blank is grasped in the left hand with the palm upward, the thumb engaging the corner of the carton at line 16, and the fingers (except the forefinger) engaging the corner at line 20. The forefinger is placed in one of the holes 58 in the bottom 34, as shown in Figure 2B, and pressure is exerted between the thumb and the fingers engaging the corner at 20. This causes the blank to bend along lines 14 and 18 and erects the front panel 32 and the rear panels 28 and 36. The free edge of the cushion 26 slides along the inner surface of the front panel 32 until it reaches the corner at line 16. At the same time the forefinger exerts an upward force on the under side of the cushion, causing it to bend along line 44 as shown in Figure 2B. The pressure between the thumb and the three fingers engaging the corner at line 20 is continued until the carton assumes an over-square configuration as indicated by the phantom lines in Figure 2B. When this occurs, the free edge of the cushion 26 slides downwardly along the inner surface of the front panel 32 into the corner at line 18. The cushion then assumes an inverted V-shape with a pair of surfaces 26a, 26b sloping downwardly toward the bottom 34 from a ridge at line 44.

This invention relates to a carton construction and more particularly to a carton for fragile articles which is constructed from a single blank.

In the storing and shipping of fragile articles, in particular eggs or the like, special precautions must be taken to ensure that the cartons or boxes which receive such articles offer sufficient protection to prevent breakage of or damage to their contents. For economic reasons, egg cartons must in addition be inexpensive and relatively simple in construction. Cartons employed heretofore, both the pressed pulp type and the type formed from fibrous sheet material, are deficient in one or more respects. A common failing of the prior art is the inability to provide a practical, inexpensive carton which will offer sufficient protection to its fragile contents. In attempts to provide the necessary protection, cartons have been manufactured which are impractical because of their complex construction. The simpler cartons have failed to provide adequate protection.

Accordingly, it is a principal object of the present invention to provide a unique carton which overcomes the defects of the prior art.

Another object of the invention is to provide a novel carton which may be formed from a single blank of sheet material.

A further object of the invention is to provide a unique carton blank.

An additional object of the invention is to provide a carton which may be erected from a blank positively and with great speed and simplicity.

Yet another object of the invention is to provide a carton having a novel cushion construction.

Still another object of the invention is to provide a unique cellular carton.

The foregoing and other objects of the invention and the manner in which such objects are accomplished will become more apparent in the following detailed description of the invention taken in conjunction with the accompanying drawing wherein:

Figure 1 is a plan view of an unfolded blank of the invention in its preferred form;

Figure 2A and 2B are end elevation views of the carton of the invention in different stages of its erection;

Figure 3 is a perspective view of the carton of the invention in its fully erected state and ready to receive eggs or the like; and

Figure 4 is an end elevation view of the carton of the invention shown with eggs inserted therein and the cover closed.

Briefly, the objects of the invention are accomplished by providing a single blank which is scored and folded to form a carton having front, rear, bottom and top panels, a cover, and an inverted V-shaped cushion supported within the foregoing panels. The cushion is arranged to cooperate with sections of the top panel which are constructed so as to form transverse partitions within the carton. The blank may be provided to the packer in

Referring to Figure 3, the end sections 64 of the top are bent downwardly (along the dotted lines 54 in Figure 1) and depend into the end slots 46 (Figure 1) of the cushion which now have become triangular notches in the ridge of the cushion. This bending may be conveniently done simultaneously with the first and second finger of each hand. The center sections 66 of the top are then bent downwardly in a similar manner. Intermediate sections 68 may be bent downwardly manually, if desired, but where speed is of the essence, these sections may be erected automatically by placing eggs in the cells between each pair of intermediate sections. Sections 64, 66, and 68 when folded downwardly become transverse partitions of the carton. The side edges of the partitions engage the front and rear panels of the carton respectively, and maintain the carton in a stable rectangular form. The lower edges of at least some of the partitions are curved as indicated at 70 in Figure 3 to impart a corresponding curvature to the surfaces of the cushion 26. Each of the notches 46 at the ridge of the cushion has a vertical side formed by the side of the corresponding triangular slot of the blank which is perpendicular to the ridge line 44, so that a surface of each partition may abut this side of the notch below it and be held substantially vertically. Each of the notches slopes downwardly from the vertex of the triangular slot at the ridge line toward its vertical side, so that the partitions slide easily into the corresponding notches. It is thus apparent that the partitions fit within the corresponding notches of the cushion and that the cushion extends above the lower extremities of the partitions so as to serve as a longitudinal divider for the carton. Two rows of cells are thus formed by the cushion and the partitions.

When the eggs are inserted, as illustrated in Figure 4, they extend above the front panel 32. The rear panel 36 is high enough to accommodate the eggs, however, and when the cover 38 is closed, with the tongues and grooves of the lip 40 interlocking with the adjacent edges of the top 30 in a well known manner, the height of the lip when added to that of the front panel equals the height of the rear panel 36. The slits 48 of the cushion provide convenient score lines for the curvature of the cushion surfaces and for the reception of the adjacent surfaces of the eggs. The articles are supported on the cushion above the bottom of the carton and are thus isolated from shocks applied to the bottom. Portions of at least some of the partitions, such as 68a in Figure 3, extend upwardly to engage the underside of the cover 38 and thus protect the articles from shocks applied to the cover. It will thus be apparent that a carton is provided which offers adequate protection for fragile articles, which is

strong yet simple to erect, and which may be formed economically from a single blank.

While a preferred embodiment of the invention has been shown and described, it will be apparent to those skilled in the art that modifications may be made in this embodiment without departing from the principles of the invention. Accordingly, this embodiment is exemplary, rather than restrictive of the invention, the scope of which is defined in the appended claims, and those modifications which fall within the meaning and range of equivalency of the claims are included therein.

What is claimed is:

1. A collapsible egg carton formed from a single integral blank comprising adjacent panels delineated by parallel weakened lines and including successively a rear panel, a bottom panel, a front panel, a top panel and a lap panel secured to the inner face of the rear panel, said panels defining a carton having a rectangular cross section, said blank having a terminal cushion panel of inverted V-shape provided with a central hinge line at the apex of the V and provided with a free edge positioned in the front bottom corner of the carton, said top panel having transverse and longitudinal cut lines defining turnable partitions coacting with said V-shaped cushion to form cells, said carton being collapsible along a plane diagonal relative to said rectangular cross section of the carton, with said cushion panel lying flat in said plane.
2. A carton as set forth in claim 1, wherein said bottom panel has a finger hole for facilitating the setting up of the carton, said finger hole being located so as to allow a finger to push against the underside of the cushion member to form said inverted V-shape as the carton is erected.
3. A carton as set forth in claim 1, wherein said rear panel extends above said front wall and has a cover for said carton hinged thereon.
